UNITED STATES PATENT OFFICE.

KARL PRINZ ZU LOEWENSTEIN, OF NECKARGEMÜND, GERMANY.

PROCESS FOR REMOVING SLAGS FROM FURNACES AND MEANS FOR CARRYING OUT
THE SAME.

1,128,255.

Specification of Letters Patent.

Patented Feb. 9, 1915.

Application filed November 25, 1912. Serial No. 733,551.

To all whom it may concern:

Be it known that I, KARL PRINZ ZU LOEWENSTEIN, a citizen of the German Empire, residing at Neckargemünd, in the Grand 5 Duke of Baden, Germany, have invented in certain new and useful Improvements in Processes for Removing Slags from Furnaces and Means for Carrying Out the Same; and I do hereby declare the following 10 to be a full, clear, and exact description of the invention, such as will enable others skilled in the art to which it appertains to make and use the same.

The invention relates to a new process 15 for removing the slags from furnaces and more especially from furnaces of that kind, in which the flames and gases of combustion burn downward through the grate. The slags must be removed after a certain time 20 of working and this must be repeated in certain predetermined intervals. This cleaning of the grate, if done in the usual manner, offers considerable inconveniences and many disadvantages for the working. For 25 instance the layer of coals must burn down so deeply, that the grate-bars nearly become free. The thin layer remaining upon the grate is no more covered with freshly inserted black coals, *i. e.* not yet burning coals 30 and is moreover in incandescent condition; the heat radiating against the stoker, when taking away the slags, is therefore nearly unbearable and his work so hard and troublesome, that often it is not done with sufficient 35 care. The difficulty of the work is still increased by the reason, that the slags must be lifted and that small pieces only can be removed at the time, on account of the soft condition of the slags. Besides it may happen 40 that the fire is extinguished completely and must be relighted, which causes a long interruption and delay of the working.

Now it has been known in furnaces with upward burning flames to drive grate-bars 45 transversely into the shaft of the furnace for the purpose of cleaning the grate and removing the slags; but it has not yet been tried, to use this false grate also in furnaces with downward burning flames, on 50 account of the great difficulties, which must be overcome in order to remove the slags from furnaces of this kind. Especially the inconvenience in the known device, that the cleaning of the real grate must be carried

out immediately after the insertion of the 55 false grate in order to prevent this latter from being burned, which causes an interruption of the working, renders impossible the employment of the false grate in furnaces with downward burning flames. 60

The new process permits the removal of the slags without special effort for the stoker and without the danger of an interruption of the working. For this purpose a space is produced above the grate before removal 65 of the slags, so that the grate is free and the slags may easily be removed, whereas the fuel above burns as before. The best way to obtain this end is to separate a certain, suitably thin layer above the grate and burn out 70 the same separated from the rest of the fuel, so that the grate lies free. The separation of this layer can be attained by already known false grate at the proper time, which is inserted several inches above the true 75 grate, so that there exists a space between the two grates.

The false grate consists preferably, as the true grate of furnaces with downward burning flames of a system of tubes that are 80 passed by a liquid. After some time the coals between the grates will be burned and the slags lying on the true grate may be taken away by the stoker without special difficulty and without interruption of the 85 working. If the slags are cleaned away, the false grate is drawn back again.

Means for carrying out this process are illustrated in the accompanying drawing, in which—

Figure 1 is a vertical section of a furnace 90 provided with the improvement, Figs. 2-6 are plan views of various forms of the false grate and the true grate.

The furnace *a* and the water cooled true 95 grate *b* are of the usual construction. According to the present invention, some time before the slags are to be removed, a false grate *c* is introduced above the grate *b*; the two grates having suitably only a small distance between them (Fig. 1). If the coals lying between the two grates *c* and *b* are burned, the slags on the grate *b* can easily be removed laterally through doors and other suitable apertures. 100

The tubes of the false grate *c* connect with cooling coils *h* surrounded by a container *k*. The cooling coils *c* may be kept 105

cool by a cooling fluid in the container *k* or in any suitable manner.

In the form of execution shown in Fig. 2 every bar of the false grate *b* consists of an internal tube *d* which is situated in an external tube *e*. The colder liquid passes firstly through the inner tube *d* and then enters into the external tube *e*.

Figs. 3 and 4 are modified forms of the 10 false grate, in which the false grate consists of separate tube-elements *f* that may be simply or repeatedly bent.

The forms of execution shown in Figs. 5 and 6 illustrate constructions of the true 15 grate *b*, the grate bars being suitably constructed in the manner shown in Fig. 2.

Having now particularly described and ascertained my invention, I declare that what I claim is:

20 1. In a down draft furnace, the combination, with the furnace and the true grate thereof, a false grate adapted to be moved into slightly spaced relation with and above the true grate, and means for cooling the 25 false grate.

2. In a down draft furnace, the combination, with the furnace and the true grate thereof, a false grate adapted to be moved into slightly spaced relation with and above the true grate, and means movable with the false grate for supplying a cooling liquid to the interior of the false grate.

3. In a furnace, the combination, with the furnace and the true grate thereof, of a 35 tubular false grate adapted to be moved into slightly spaced relation with and above said true grate, and means movable with the false grate for introducing a cooling liquid into the tubes of the false grate.

40 4. In a furnace, the combination, with the furnace and the true grate thereof, of a tubular false grate adapted to be moved into slightly spaced relation with and above said true grate, means movable with the false 45 grate for introducing a cooling liquid into the tubes of the false grate, and a door in

the furnace at the end of the space between the grates.

5. In a down draft furnace, the combination of a stationary water-cooled true 50 grate sloping toward the forward end of the furnace; a tubular false grate adapted to be moved into slightly spaced relation with and above the true grate; a coil communicating with the tubes of the false grate; and a 55 tank surrounding the coil, said tank, coil and false grate being connected with each other and all adapted to move together at the same time.

6. In a down draft furnace, the combination 60 of a movable tank; a coil within said tank and movable therewith; a grate movable with said coil and tank and movable pipes connecting said coil and grate and movable therewith. 65

7. In a down draft furnace, the combination of a movable tank; a coil in said tank and movable therewith; and a movable grate connected with the coils, said coil, tank and grate being movable together a distance substantially equal to the length of the false 70 grate.

8. In a down draft furnace, the combination of a stationary water cooled true grate sloping toward the forward end of the furnace and having upturned inner ends; a tubular false grate adapted to be moved into slightly spaced relation with and above the true grate; a coil communicating with the tubes of the false grate; and a tank surrounding the coil, said tank, coil and false 75 grate being connected with each other and all adapted to move together at the same time a distance substantially equal to the length of the false grate. 80

In testimony whereof I affix my signature in presence of two witnesses.

KARL PRINZ ZU LOEWENSTEIN.
